Thomas Wallace,
Inventor

By his Attorney

John Freeman.

UNITED STATES PATENT OFFICE.

THOMAS WALLACE, OF NEW YORK, N. Y.

CONDUIT.

SPECIFICATION forming part of Letters Patent No. 431,630, dated July 8, 1890.

Application filed June 27, 1889. Serial No. 315,730. (No model.)

To all whom it may concern:

Be it known that I, THOMAS WALLACE, a citizen of the United States, residing in the city, county, and State of New York, have invented certain new and useful Improvements 5 in Conduits, of which the following is a specification.

My invention relates to certain improvements in conduits for electrical conductors, 10 and more especially to those of the character set forth in my application, Serial No. 227,603, upon which Letters Patent issued October 24, 1887, and my application Serial No. 295,569; and my improvements consist in constructing 15 a conduit for any desired purpose, as fully set forth hereinafter, so as to secure a practically continuous and homogeneous structure, and in the means hereinafter set forth for supporting the conductors.

20 In the accompanying drawings, Figure 1 is a transverse section illustrating a conduit built in accordance with my invention. Fig. 2 is a sectional plan at the junction of two conduits with a man-hole. Fig. 3 is a sectional elevation on the line 3 3, Fig. 2. Fig. 25 4 is a longitudinal sectional plan through the conduit. Fig. 5 is a transverse section illustrating the combination and arrangement with the conduit of a support—as, for instance, 30 of electrical conductors.

It is common in building electric or other conduits to make the same of connected sections of clay or other material, the said sections being connected by means of cement, 35 and the material of which they are composed being friable and easily broken. The cementing materials employed differ in character from that of which these sections are composed, so that there never can be a very strong union 40 between the two, and the sections are liable to be separated from each other by the sinking of the earth, while they are also liable to be disintegrated from the said cause or from superposed pressure or from vibrations resulting from heavy traffic on the streets.

45 To construct a conduit which is not open to the objections above specified, I make use of blocks of any suitable form composed of a suitable composition, and I cement the blocks 50 together by means of the same composition

as that of which they are made, so that there is an absolute union between each block and the cement, while the conduit built in this manner is practically continuous and homogeneous throughout its extent. As a result, 55 there are practically no joints in the completed structure, and therefore practically no lines of weakness, as in conduits built up in the ordinary manner, while the conduit may be erected with the same facility as one built 60 up of bricks and mortar and at a fraction of the expense of one made up of molded sections connected by cemented joints.

While the blocks of which the conduit is built may be made of any suitable composition, I prefer to mold them from a composition of calcined earth or clay and asphalt, preferably with the mixture of asbestos. In making such mixture I use the ingredients in about equal proportions, although the proportions may be varied to a great extent, mix the same hot, mold the blocks thereof in suitable molds, and in building the structure I apply the cement made of the same materials in a highly-heated condition, also heating the 70 faces that are applied to the cement, so that there will be an absolute and perfect union between the cement and the blocks. The blocks may be in any form, preferably in the shape of slabs or bricks A, and so arranged 75 as to leave a continuous longitudinal chamber X for the reception of the contents.

At the intersection of streets, or where two or more conduits must be brought together, I form a man-hole by making a hollow cylindrical structure B, built up of the blocks A, cemented together, as before described, and connected in a like manner at the termini at the different conduits D D, with an opening 80 in the side of the man-hole wall opposite the 85 channel in each conduit.

Where the conduit is to be used for electric conductors and it is desired to extend any one of the conductors laterally to a house or elsewhere, it may be passed directly through 90 the walls of the conduit, inasmuch as the latter, when made as above described, is a perfect non-conductor. I prefer, however, to deflect one of the walls of the conduit to form a 95 loop C, as shown in Fig. 4, wherever a lateral

conductor is to be run, the said loop inclosing a small lateral chamber α , communicating with the main chamber of the conduit, which chamber α may be opened at the top or side for the passage of the conductor.

The conduit may be ventilated by connecting it with stand-pipes, chimneys, or lamp-posts, and it may also be provided with a portable frame I , adapted to fit transversely within the conduit, as shown in Fig. 4.

When the frame is to be used for electric conductors, it can be made to support transverse rods a , upon each of which turns loosely two or more grooved disks or rollers, and a series of such frames carrying such rollers are arranged at proper intervals in the conduit, and the conductors Y are extended through the conduit lying in the grooves of the spools. By this arrangement I am enabled to readily place the bearings for conductors in suitable position. By having the ventilating pipes or passages the free play of the air around each conductor is secured, so that instead of moisture being deposited upon the conductor it is carried from the conduit.

In order to facilitate the passage of the conductors through the man-hole from one conduit to another, I provide the latter with roller-bearingssuitably arranged to support the conductors. Thus opposite each opening y in the wall of the man-hole extends a rod c , supported by brackets d , upon which turn spools a' , similar to the spools a , and the conductors from each opening y are passed around said spools as bearings, and then conducted either directly to the spools at the opening leading to the other conduit into which the conductors are to extend or around interme-

diate spools arranged as bearings adjacent to the wall of the man-hole.

Although I have shown and described a series of electric conductors with the conduit, I make no claim to such conductors, but have only introduced them for the purpose of illustrating one use to which the conduit could be applied.

Without limiting myself to the precise construction and arrangement of parts shown, I claim—

1. A homogeneous conduit consisting of 50 blocks cemented together by a cement consisting of the same mixture or composition as that of which the blocks are molded, substantially as set forth.

2. A conduit consisting of blocks composed, 55 mainly, of a composition of asphalt and calcined earthy matter connected by a cement of the same materials, substantially as set forth.

3. A homogeneous conduit consisting of blocks cemented together by cement consisting of the same mixture or composition as that of which the blocks are molded, one of the walls of which is deflected to form a loop inclosing a small lateral chamber α , substantially as described.

4. The combination, with a continuous and homogeneous conduit, of frames fitted transversely within the conduit, substantially as described.

In testimony whereof I have signed my 70 name to this specification in the presence of two subscribing witnesses.

THOMAS WALLACE.
